UNITED STATES PATENT OFFICE.

HAMLING TATUM, OF DOTHAN, ALABAMA.

CLOTHESLINE.

Application filed February 11, 1927. Serial No. 167,492.

This invention relates to clothes lines and has for its object the provision of a novel clothes line constructed of a plurality of link members connected in series and each formed 5 to provide clamping means for garments and the like whereby they will be properly suspended for drying purposes.

An important object of the invention is to provide a device of this character in which 10 each link member is formed of a minimum number of parts so that the cost of production will be very low.

To the attainment of the above recited objects, the improvement resides in the construction, combination and arrangement of parts, as hereinafter described and definitely claimed.

In the drawings:

Figure 1 is a side elevation of a clothes line 20 in accordance with this invention.

Figure 2 is a top plan view of one of the members constituting the improvement.

Figure 3 is a perspective view thereof.

The clothes line may be of any length and 25 embodies a chain of interlinked elements, constructed of wire, treated to be rust proof, the wire also having a natural resiliency.

Each of the link elements constituting the line includes a length of wire bent near its 30 center to provide an eye 1 and two parallel strands 2^a that extend from said eye. The strands are bent as at 2 to form an acute angle and from the bend 2 the strands are spaced apart to provide a pair of portions 3 and 4 which are parallel for a distance from the 35 bend 2 but which cross each other at different points throughout the remainder of the length thereof. The portion 4 terminates in an inwardly directed hook 5, and the portion 40 3 extends beyond the hook 5 and is bent upon itself to provide an eye 6. The end of the portion 3 after being formed into the eye 6 is directed inwardly and is coiled as at 7, around both of the portions, one of the convolutions 45 of the coil being in contact with the free end of the hook 5.

I also provide a second length of wire 8 which is located between the portions 3 and 4 of the strands 2, at the opposite sides of the points of crossing of the latter, one end of the 50 second length of wire being extended at an angle as at 9 to provide what may be termed a jaw that terminates in a hooked end 10 to receive the eye 1 the other end of said length being held in the coiled end 7 as best shown in 55 Figure 1. The bend 2 of one link element is engaged through and within the eye 6 of the adjacent link element of the line, and it will be apparent that when the corner of a cloth article to be suspended on the line is passed 60 between the jaw 9, of the strand 8 and the portions 3 and 4 of the strands 2, and the said cloth article is forced in the direction of the eye 6, the jaw 9 and portions 3 and 4 will compress the cloth article and hold it associated 65 with the element. A pull upon the cloth in a reverse direction will permit of the same being readily separated from the gripping portions of the line.

Having described the invention, I claim:— 70

A clothesline composed of a plurality of interlinked elements, each comprising a length of wire bent near its center to form an eye and two parallel strands extending from the eye, said strands being bent near said eye 75 to form an acute angle, said strands crossing each other at points spaced from said angle and from each other, the end of one strand being bent to form a hook, and the other extending beyond the hook and being bent to form 80 an eye and formed into a coil around the two strands adjacent said hook, a second length of wire connected at one end with said first named eye and extending between said 85 strands on opposite sides of the crossings of the strands and having its other end held in said coil.

In testimony whereof I affix my signature.

HAMLING TATUM.
